(57) **CLAIM**

The ornamental design for a flush mount kit, as shown and described.

DESCRIPTION

FIG. 1 is a front isometric view of a touch panel installed in a flush mount kit in the flush position; and,
FIG. 2 is a front isometric view thereof in the extended position.

In the drawings, the broken lines are for the purpose of illustrating environment only and form no part of the claimed design.

1 Claim, 2 Drawing Sheets

FIG. 1

FIG. 2
